CLAIM

The ornamental design for a beach toy, as shown and described.

DESCRIPTION

FIG. 1 is a perspective view of a beach toy showing my new design.

FIG. 2 is another perspective view of the beach toy of FIG. 1.

FIG. 3 is a front view of the beach toy of FIG. 1.

FIG. 4 is a rear view of the beach toy of FIG. 1.

FIG. 5 is a side view of the beach toy of FIG. 1.

FIG. 6 is an opposite side view of the beach toy of FIG. 1.

FIG. 7 is a top view of the beach toy of FIG. 1.

FIG. 8 is a bottom view of the beach toy of FIG. 1.

FIG. 9 is a further perspective view of the beach toy of FIG. 1 in a state of use; and,

FIG. 10 is an enlarged view of the selected portion 10 in FIG. 1.

The broken lines shown in the drawings depict portions of the beach toy that form no part of the claimed design. The dot-dash broken lines in the drawings illustrate the periphery of the enlarged views of the beach toy and form no part of the claimed design.
